PERMUTATION-LOCK.

1,393,269.

Specification of Letters Patent. Patented Oct. 11, 1921.

Application filed November 14, 1919. Serial No. 337,933.

To all whom it may concern:

Be it known that I, EUGÈNE MAURICE OCTAVE DESCALLES, manufacturer, subject of the Republic of France, and resident of Paris, France, have invented certain new and useful Improvements in Permutation-Locks; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

This invention relates to permutation locks, and more particularly to locks in which a set of wheels is manipulated from the outside of the lock case by means of an operating knob, these wheels being brought to different predetermined positions corresponding to the letters or digits of the "combination" selected. The permutation wheels operate to turn a corresponding number of wheels which form a locking mechanism, the arrangement being such that when all of the permutation wheels have been brought to their respective predetermined positions, the locking wheels will have been brought to unlocking position, thus enabling the opening of the lock.

In effecting the setting or adjustment of the permutation wheels, the latter are initially turned in one direction by the operating knob, during the course of which movement they are successively connected together to move in unison and are ultimately brought into a predetermined fixed position which is the position from which they start during their subsequent manipulation to effect unlocking. This subsequent unlocking manipulation is carried out by turning the knob first in one direction and then in the other, and it results in the stopping or disengagement of each wheel on reaching its selected position, so that by the time that the last wheel has completed its setting movement, the locking mechanism has been simultaneously unlocked.

The invention resides in the particular construction and arrangement of parts comprised in the permutation and locking mechanisms, and in the particular devices

associated with said mechanisms for effecting the above-mentioned movements thereof, all as hereinafter fully explained. 55

An embodiment of the invention is illustrated in the accompanying drawings, wherein:—

Figure 1 is a perspective view of the improved lock, with the cover plate omitted 60 and the side wall of the case partly broken away.

Fig. 2 is a perspective view of the operating knob and its attached permutation wheel.

Figs. 3 and 4 are obverse and reverse perspective views of the second permutation wheel. 65

Figs. 5 and 6 are similar views of the third permutation wheel.

Fig. 7 is a plan view of the under or reverse side of the second wheel. 70

Fig. 8 is a perspective view of the lock case with the permutation and locking mechanisms omitted to show the various pivot pins or studs. 75

Fig. 9 is a perspective view of the slide for transmitting the movements of one of the wheels to another.

Fig. 10 is a perspective view of a removable plug or bushing which is fitted in an 80 opening in the bottom of the case and which is operated incidental to a change in the combination.

Referring more particularly to the drawing, there is represented a lock comprising a 85 cylindrical case, indicated generally at 29, (Fig. 8), a suitable cover plate, illustration of which is omitted, and a pivotally-mounted shackle 1. The shackle is provided adjacent its free end with a notch 4 for engagement by a projection or finger 2 on a locking lever 3 which is mounted for rocking movement on a pin 9, whereby the shackle is retained in closed position; said lever being provided with two additional projections or 90 fingers 7 and 38. The finger 7 is designed for coaction with the locking mechanism, here shown as comprising three superposed wheels or gears 5 which are loosely mounted on a hollow pin 6 (Fig. 8) formed with a 95 longitudinal slot. The gears 5 are each formed with a slot 8 which extends radially from its central opening; these slots being brought into registration with the pin slot 100

in one position of the gears so as to form a lateral continuation of the pin slot. The finger 7 extends into the open end of the pin, as indicated in Fig. 1, and is held therein 5 until the rotation of the locking gears 5 effects the registration of their slots 8 with the pin slot, whereupon outward movement of the locking lever is free to take place with resultant disengagement of finger 2 from 10 notch 4. The other projection or finger 38 on the locking lever is so arranged that when the shackle 1 is swung outward or opened, after the locking lever has been disengaged from the shackle, the pivoted end 39 of the 15 latter will extend across or behind said finger and thus prevent the locking lever from being moved back into active position until the shackle has first been moved inward.

The locking mechanism comprising the 20 three gears 5 is designed for coaction with the permutation mechanism which, according to the present invention, embodies three superposed gears 10, 11 and 12 loosely mounted for individual movement on a pin 25 or stud 13. These gears are utilized to drive the locking gears 5 which are normally meshed therewith but can be unmeshed therefrom when it is desired to change the key word or number of the "combination," 30 for which purpose the hollow carrier pin or stud 6 is mounted on a plate 33 which is pivoted on the stud 9 so that it may be swung toward or away from the permutation gears. In the construction illustrated, 35 the stud 9 has coiled around it a torsion spring 34 (Fig. 1), one end of which bears against a lug 35 formed on the locking lever 3 while the other end engages a lug 36 formed on the carrier plate 33, so that the 40 said spring tends not only to swing the carrier plate in a direction to mesh the locking gears with the permutation gears, but also to engage the locking finger 2 on the lever 3 with the shackle notch 4. The dis- 45 engaging movement of the carrier plate is effected from the outside of the case by means of a plug or sleeve 31 (Figs. 1, 8 and 10), which is rotatably fitted in an opening in the back of the case and is formed with 50 a circumferential notch or recess 32 and with an outer notch 41, the latter being designed to receive the edge of a screw driver or coin for turning the plug. The notch 32 receives the adjacent edge of the carrier plate 33 55 therein and is so shaped as to exert a camming pressure on said plate when the plug is turned in the proper direction, thereby forcing the carrier away from the permutation gears.

60 The manipulation of the permutation gears serves to move them individually and successively, beginning with the bottom gear 12, from a predetermined fixed position into a position corresponding to that in which 65 the associated locking gears 5 have their

slots 8 registering with the slot in pin 6. This operation takes place after a preliminary setting or adjusting operation herein-after explained, and it is effected primarily by means of the top gear 10 which is provided with a knob 14 (Fig. 2) suitably fixed to its hub and projecting through an opening in the front of the case, the movement of said gear being transmitted to the intermediate gear 11 and thence to the bottom gear 75 12. The transmission movement from the operating or manually-turned top gear 10 to the intermediate gear 11 may be effected by extending one of the teeth of gear 10 rearwardly to form a projection or lug 15 (Fig. 80 2) for engagement between two teeth 16 and 17 of unequal lengths which are provided at one end of a bar 18 (Figs. 3 and 9) slidably mounted on the upper or obverse face 85 of gear 11 and held against lateral displacement in some suitable manner. The other end of the sliding bar is provided with a depending projection or tooth 19 (Figs. 3, 4 and 9) which extends through an opening in gear 11 large enough to enable the play 90 necessary for the sliding movements of the bar; and the under or reverse side of said gear is provided, in turn, with a depending tooth 21 (Figs. 4 and 7) adapted for engagement with the projecting upper end of a 95 stop pin 22 (Figs. 5 and 6) carried by the bottom gear 12. This pin 22 is fixed to the free end of a leaf spring 28 (Fig. 6) which is attached at its other end to the under or reverse face of gear 12; said pin extending 100 loosely through an opening or hole in the gear, which latter is further provided on its upper or obverse face with an inclined or wedge-shaped lug 20 (Fig. 5) for coaction 105 with the projecting end of tooth 19. The pin 22 extends on both sides of its carrier spring 28, its lower portion coacting with a fixed cheek plate 40 (Fig. 8) arranged on the bottom of the case and having a circular 110 cut-out portion or opening disposed concentric with stud 13; the said case bottom being additionally provided with a recess or depression 30 wherein pin 22 is adapted to seat when brought into alignment therewith. The permutation gears 10, 11 and 12 have individual pawls 23, 24 and 25 (Fig. 1) associated with them which are subjected to the action of springs 26 and which produce a 115 succession of sharp, audible clicks consequent upon their passage over the teeth of 120 the gears; and in order to lock the permutation mechanism in the above-mentioned preliminary position which is used as a base for the combination selected and which may be termed the zero position, one gear (in this 125 instance, the intermediate gear 11) is provided with a short or mutilated tooth producing a gap which is indicated at 27 (Fig. 7) and which, when engaged by the associated pawl 24, prevents the continued rota- 130

tion of said gear in one direction and, consequently, the further operation of the mechanism in question.

The permutation mechanism is brought 5 to the position just mentioned by the preliminary manipulation of the knob 14, which is turned in a clockwise direction, thereby rotating gear 10 in the same direction. During the course of this movement 10 of gear 10, its lug or tooth 15 picks up the long tooth 16 on the slide 18 carried by gear 11, which latter is then rotated in unison with gear 10; and after the two gears have moved together through a certain 15 angle, the tooth 21 on the under side of gear 11 picks up the pin 22 carried by gear 12, thus connecting all three gears together for unitary movement. This movement of the gears continues until the intermediate 20 pawl 24 engages in the gap formed by the mutilated tooth 27, the position of the three gears 10, 11 and 12 at such time being the zero position above referred to.

Thereafter the permutation mechanism is 25 manipulated to bring the permutation gears into positions corresponding to the combination selected and which, in turn, bring the gears 5 of the locking mechanism into position to release the locking lever 3. In carrying out this new manipulation, the knob 14 is first turned from right to left—i. e., counter-clockwise—during which time its tooth 15 engages the short tooth 17 on slide 18 and in that way drives the intermediate 30 gear 11, the pawl 24 offering no obstruction to this reverse rotation of said gear. The tooth 17 is rounded, as shown in Fig. 9, and the pressure exerted against it by tooth 15 has a tendency to force the slide 35 away from it, which would obviously disengage the two coacting teeth and uncouple the two gears were it not for the fact that in the zero position of the gears the projecting end of the tooth or lug 19 at the 40 opposite end of the slide is in engagement with the stop lug 20 on gear 12 which holds it against such movement. The tooth 21 on gear 11 is engaged with the projecting upper end of pin 22 at that time and hence 45 all three gears move in unison, turning the corresponding locking gears 5 with them. The pawls 23, 24 and 25, as previously stated, produce sharp clicks during their 50 passage over the teeth of the permutation gears, and these audible clicks are counted in accordance with the combination selected, each click indicating a movement of the gears through one tooth space. When the 55 number of clicks equals the first figure of 60 the combination, the bottom gear 12 is dropped and is held in set position by means of its pawl 25. During the movement of gear 12, the lower end of the pin 22 engages and rides along the cheek 40, 65 and as such movement continues it leaves

said cheek and ultimately seats itself in the recess 30, thus withdrawing its upper end from the path of tooth 21. The knob is then turned in the opposite direction for the second number of the combination, the tooth 70 15 on gear 10 this time bearing against tooth 16 on slide 18 and thus effecting the driving movement of gear 11, and the lug 19 on said slide moving away from tooth 20. The rotation of the two gears continues until the number of clicks equals the second figure of the combination, whereupon the direction of rotation of the knob is again reversed. When the reverse movement of the knob and, hence, 80 of its connected gear 10 commences, tooth 15 on said gear is caused to bear against the short rounded tooth 17; but since lug 19 is no longer engaged with tooth 20, there will be nothing to prevent the 85 displacement of the slide which, in consequence, will be forced endwise away from tooth 15 by the pressure exerted by said tooth upon tooth 17, uncoupling the two gears. Hence during the further movement 90 of the knob, gear 11 will remain stationary, being held by its pawl 25, while gear 10 will continue to turn and will finally be brought into the desired position, thus completing the combination. The corresponding 95 locking gear 5 is brought into position to register its slot 8 with the slot in stud 6 as each permutation gear assumes the proper selected position, so that when the setting of the last or top gear 10 is completed the shackle will be unlocked and can 100 be released from lever 3.

The manipulation of the main gears 10, 11 and 12 incidental to the opening of the lock obviously displaces them from the 105 fixed or zero position into which they were previously brought during the initial or preliminary setting operation; and they must, therefore, be restored to that position before again being adjusted in conformity 110 with the combinations. Hence there are really two setting operations to be carried out on the gears each time that the lock is opened, the first operation setting the gears preliminary to the second operation. In 115 effecting the first operation, the knob 14 is always turned in the same direction (clockwise); and during this operation the tooth 19 on the slide 18 is caused to engage with tooth 20, such engagement serving to force the slide endwise in a direction to cause its teeth 16 and 17 to straddle the tooth 15 on the driving gear 10. According to the second or main setting operation, the knob 14 and gear 10 are first turned counter-clockwise to set the bottom gear 12, then clockwise to set the intermediate gear 11 and then counter-clockwise again to set the top gear, the engagement between the teeth 19 and 20 continuing throughout the first 120 130

counter-clockwise movement, as has already been explained, to prevent disengagement of tooth 15 from tooth 17.

I claim as my invention:—

- 5 1. In a permutation lock, the combination, with a shackle and a locking element engageable therewith; of a permutation mechanism for controlling the engagement and disengagement of the locking element, comprising a series of superposed wheels, an operating knob connected to one permutation wheel, a projection on said wheel, a slide carried by another permutation wheel and having teeth for engagement by said projection to releasably couple the first and second wheels together, means for controlling the movements of the slide to regulate the coupling and uncoupling of said first and second wheels, and means for releasably coupling the second wheel to a third permutation wheel.
- 10 2. In a permutation lock, the combination, with a shackle and a locking element engageable therewith; of a permutation mechanism for controlling the engagement and disengagement of the locking element, comprising a series of superposed wheels, an operating knob connected to one permutation wheel, a projection on said wheel, a slide carried by another permutation wheel and having two teeth of unequal lengths at one end between which said projection is adapted for engagement to releasably couple the first and second wheels together, a lug on a third permutation wheel engageable with the other end of the slide to control its movements and thereby regulate the coupling and uncoupling of said first and second wheels, and a resilient element on the third permutation wheel engageable with a projection on the second wheel to releasably couple the two together.
- 15 3. In a permutation lock, the combination, with a shackle and a locking element engageable therewith; of a permutation mechanism for controlling the engagement and disengagement of the locking element, comprising a series of superposed wheels, an operating knob connected to one permutation wheel, a projection on said wheel, a slide carried by another permutation wheel and having two teeth of unequal lengths at one end between which said projection is adapted for engagement to releasably couple the first and second wheels together, a lug on a third permutation wheel engageable with the other end of the slide to control its movements and thereby regulate the coupling and uncoupling of said first and second wheels, and means for releasably coupling the second and third wheels together.
- 20 4. In a permutation lock, the combination, with a shackle and a locking element engageable therewith; of a permutation mechanism for controlling the engagement and disengagement of the locking element, comprising a series of superposed wheels, an operating knob connected to one permutation wheel, a projection on said wheel, a slide carried by another permutation wheel and having two teeth of unequal lengths at one end between which said projection is adapted for engagement to releasably couple the first and second wheels together, a lug on a third permutation wheel engageable with the other end of the slide to control its movements and thereby regulate the coupling and uncoupling of said first and second wheels, and a resilient element on the third permutation wheel engageable with a projection on the second wheel to releasably couple the two together.
- 25 5. In a permutation lock, the combination, with a shackle and a locking element engageable therewith; of a permutation mechanism for controlling the engagement and disengagement of the locking element, comprising three superposed wheels, one provided with an operating knob and with a projection, the second having an opening formed through it and a lug on its under face, and the third having an opening formed through it and a lug on its upper face, a slide mounted on the upper face of the second wheel and having teeth at one end for engagement by the projection on the first wheel and a projection at its other end extending through the opening in the second wheel for engagement with the lug on the third wheel, and a spring plate fixed to the under face of the third wheel and having an upstanding pin which extends through the opening in said third wheel for engagement by the lug on the second wheel.

In testimony whereof I affix my signature in presence of witnesses.
